INTERNAL COMBUSTION ENGINE

Clyde R. Paton, Birmingham, Mich., assignor to
 Packard Motor Car Company, Detroit, Mich.,
 a corporation of Michigan

Application February 1, 1933, Serial No. 654,608

9 Claims. (Cl. 123—179)

This invention relates to internal combustion engines and more particularly to the mixture control mechanism for such engines.

In starting internal combustion engines, it is necessary to enrich the mixture fed to the cylinders and, for this purpose, most engines are equipped with choking devices which result in the formation of a combustible mixture rich in fuel. Under certain conditions, such as when the choke mechanism is manually operated, it has been found desirable to connect the throttle, which controls the volume of combustible mixture, to the choke mechanism so that the engine will tend to develop more speed or power while choked and thereby remind the vehicle operator that the engine is still choked, thus serving to prevent long continued engine operation under choked conditions, which, it is well known, results in excessive fuel consumption, oil dilution, and consequent motor wear. However, in using a device of this nature, I have found that the throttle valve is sometimes too widely opened by the choke mechanism and thereby results in the formation of too lean a mixture for satisfactory starting and I have, therefore, connected the engine starting system to the throttle valve in such a way as to render the choke connection to the throttle valve ineffective while the starter is operating and effective immediately thereafter.

One of the objects of this invention is to enable the starting mechanism to make the mixture richer than the choke mechanism is able to do.

Another object of the invention is to enrich the combustible mixture supplied to an engine during the starting period without increasing the amount of mixture available until after the starting period is over, at which point it is proposed to automatically increase the amount of mixture fed to the engine to a predetermined amount, which amount shall be sufficient to maintain combustion under extreme temperature conditions.

A further object of the invention is to so control the mixture fed to the engine during operation of the starting system, and thereafter, that the volume of the mixture will be increased, and its richness decreased, immediately after the engine is started.

Another object of the invention is to provide a fuel feeding system with automatic means for increasing the supplied mixture by a predetermined amount as soon as the starting system is thrown out of operation.

A still further object of the invention is to provide a fuel feeding system with automatic

means for increasing the air fuel ratio in the combustible mixture fed to the engine as soon as the starting system is thrown out of operation.

Other objects of the invention will appear from the following description taken in connection with the drawing, which forms a part of this specification, and in which:

Fig. 1 is a partly sectioned view of a carburetor on a plane perpendicular to the throttle axis with which is associated a starting system;

Fig. 2 is a section on the line 2—2 of Fig. 1;

Fig. 3 is a section on the line 3—3 of Fig. 1 showing a detail of the carburetor controlling mechanism;

Fig. 4 is a section on the line 4—4 of Fig. 1 showing a portion of the carburetor; and

Fig. 5 is a modification of a portion of Fig. 1.

Referring to the drawing, 10 illustrates a carburetor attached to an intake manifold 11 which in turn may be associated with an engine in the well-known manner, such as is illustrated in Patent 1,122,121, to Huff dated December 22, 1914, so that the carburetor under the influence of the engine-induced suction in the manifold supplies the required air mixture to the engine in a manner which will be more fully described. Also associated with the engine in the well-known manner as is conventionally illustrated in Patent 1,116,370, to Bendix dated November 10, 1914 is a starter system including a starting motor 12 engageable in driving relation with the engine through a starting pinion 13. Suitable power means, such as a battery 14, controlled by a switch 16, is adapted to energize the starting motor. A solenoid 17, the purpose of which will be more fully described hereinafter, is included in the electrical circuit through the starter and is thus energized whenever the starter motor is operative and is de-energized upon breaking of the starter motor circuit, as by the opening of the switch 16.

More in detail, the carburetor comprises an air supply inlet 18, a throttle valve 19 mounted on a shaft 21, and a mixing chamber 22 between the air inlet 18 and the throttle valve.

23 is a float chamber or carburetor bowl containing a float valve, not shown, for regulating the level of fuel in the bowl. During normal running conditions, fuel is supplied to the mixing chamber 22 through a duct 24 connected, in a manner not shown, to the float chamber. Within the duct 24 is a needle valve member 26 controlling the supply of fuel fed through the duct to the outlet end of the expirating nozzle 27.

The nozzle 27 is situated between a pair of swingable vanes 28, of which only one is shown, forming a venturi. In the type of carburetor shown, the vanes pivot about their supports 29 under the influence of the engine suction and in so swinging lugs 31, integral with the vanes, engage a groove 31^a in the nozzle to raise the nozzle and the duct 24 in a direction away from the needle valve 26, thereby varying the effective size of the needle valve opening so that as the volume of air fed to the engine increases, the fuel volume will also increase, thus maintaining a fuel air mixture of the proper proportions until maximum power conditions are encountered when a power jet 32 comes into use and admits additional fuel.

The power jet is located between the vanes 28 and the throttle valve and there is still another passageway 33, serving as a priming jet, having an outlet located in the fuel feeding conduit beyond the throttle valve. Such jets form an auxiliary supply means for the fuel feeding system.

The power jet has a plurality of functions. In one position of the control means, nothing passes through the power jet. When the control means is in another position and the engine is idling, only air passes through the jet, but when the throttle has been somewhat further opened, air and gasoline are supplied by the power jet thereby increasing the richness of the fuel mixture. When the throttle is not very far open, there is a rotating valve means associated with the accelerating pump, to be described, which limits the air drawn through the power jet. Under either open or partially closed conditions, sudden opening of the throttle results in the depression of the pump, and a stream of liquid fuel is injected through the power jet.

The priming jet 33 is designed to function only when the control 47 is adjusted for engine starting. When this condition occurs, the pump just referred to operates, when the throttle opening mechanism is moved, to inject a stream of liquid fuel through the priming jet. This is sometimes done prior to operating the starter in order to get gasoline into the intake manifold. As the starter is operating with the throttle in wide-open position, the suction created by the engine in the manifold draws gasoline from the float chamber 23 through the jet 33 where it is mixed, in a rich mixture, with the air coming past the throttle valve. The starting mixture is enriched by closing of the throttle, it being understood that even with the throttle completely closed, some air is drawn past it by the manifold suction.

The power jet consists of the conduit 32 supported in the body of the carburetor and communicating with a passage 34 in a boss 36 projecting from the side of the carburetor above the bowl 23. The boss 36 is provided with an axial bore 37 within which is located an accelerating pump housing 38, the housing being freely slideable and rotatable in the bore. The housing itself has an axial bore 39 enlarged at its upper end to form a chamber 40 and communicating with four radial ports 41, 42, 43, and 44 located in that part of the housing which is within the boss 36. The housing extends above the boss where it is relieved on one side to form a flat face 46, and extends below the boss to a point adjacent the top of the float chamber 23. The lower part of the pump housing 38 is fixed to an operating arm 47 and is acted upon by a spring 48, attached as at 49, to the carburetor in such a manner that the spring opposes the action of the choke operating means, such as a cable 51, which is regu-

lated by a suitable choke controlling mechanism. A coil spring 52, surrounding the housing and abutting the lower part of the boss 36, engages the upper part of the arm 47 and forces the housing 38 downwardly so that its lower end engages with the top of the carburetor bowl 23. Registering with the lower end of the pump housing 38 is a sleeve 53 which projects down into the float chamber below the level of the fuel therein. The sleeve is apertured, as at 54, above the fuel level and is adapted to cooperate with the lower end of a pump plunger 56 to form the accelerating pump means for supplying fuel to the intake manifold when the plunger 56 is depressed. For this purpose, the sleeve is provided with a gravity check valve 57 and a spring 58 which normally urges the plunger 56 upward. Thus, during the upward stroke of the plunger, fuel is drawn into the space below the plunger through the valve 57. For operating the plunger, I have provided an arm 59 pivotally associated with the upper end of the plunger and with the throttle shaft 21 so that rotation of the shaft towards a throttle opened position will depress the pump plunger, forcing fuel upwardly through an axial bore 61 and a radial bore 62 in the plunger to the chamber 40 formed in the interior of the pump housing 38.

When the control member 47 is moved to one extreme position, as shown in Fig. 4, it is noted that the only outlet from the pump chamber 40 is the port 42 and the jet 33. When the control member 47 is in an intermediate position, ports 41, 42 and 43 in the pump housing 38 are closed to the chamber 40, but the port 44 is open to the chamber 40 and registers with the passage 34 and with the power jet 32. When the control member 47 is at the other extreme position from that in which the jet 33 is open, port 42 is closed off from the chamber 40, passage 41 is open to the chamber and registers with a passage 64 formed in the boss 36 and port 43 registers with the power jet 32.

Where the axial bore 39 in the pump housing 38 joins the bore 90, there is formed a shoulder 65 and there is, in the wall of the pump plunger 56, a second radial bore 66 which is adapted to be uncovered by the shoulder 65 when the throttle is wide open. It will also be noticed that there is a shoulder 67 formed on the upper part of the pump plunger 56. This is adapted, when the throttle is partially open, to close the passage 41. With the throttle in this position then, it is seen that communication between the air inlet 64 and passage 41, leading to the power jet 32, is closed but that an air inlet has been opened through the passage 66, the aperture 54, and an air inlet 68 formed in the top of the carburetor bowl so that, with the engine running, a suction is exerted on the opening 66 and on the volume of fuel in the axial bore 61 of the pump plunger. The opening 66 is relatively smaller than the passage 64 so that under these conditions both air and gasoline are drawn up through the axial bore 61 of the pump plunger through the upper chamber 63, the passages 43 or 44 and 34 to the power jet 32. These passages are co-related in their functioning to regulate the mixture in a desirable manner.

It is thus seen that under idling conditions the engine is fed by fuel passing through the nozzle 27 supplemented by air passing through the power jet 32. When the throttle is more widely opened, additional gasoline is fed through the power jet 32.

Rotation of the control arm 47 rotates, as has been previously described, the pump housing 38 and such rotation turns the flat face 46 out of contact with pin 69 carried by an arm 71 on the 5 throttle shaft 21.

A spring 72 keeps the pin 69 in contact with the upper part of the pump housing 38 and, as the housing is rotated, the pin 69 and spring 72 cooperate to open the throttle valve slightly.

10 Thus, whenever the arm 47 is in a position to cut off the air supply through the power jet 32, thereby enriching the mixture, the throttle will be open and the driver will know by the added engine speed that his engine is operating with 15 fuel in which the ratio of fuel to air is high.

When the arm 47 is finally released, the spring 18 48 draws the arm back and the pin 69 again engages the flat face 46 thereby permitting the throttle to close to idling position. The rotation 20 of the pump housing, which accomplishes this rotation of the arm, also brings the passages 41 and 43 into communication with the passages 64 and 34 so that, as the throttle is then opened, the 25 operation will be as described.

25 While it is advantageous to have a warning that the priming jet 33 is operating, it is, I have found, desirable to have a greater suction exerted on the priming jet than is possible with the 30 throttle in the cracked-open position brought about by the pin 69 engaging the cylindrical portion of the pump housing. That is to say, it is desirable to close the throttle completely while starting but, as soon as the starter ceases to function, and the engine operates on its own 35 power, it is desirable to have the throttle resume its partially opened position so that a sufficient volume of a leaner mixture may be provided to sustain engine operation.

For accomplishing this purpose, I provide a 40 connection between the starting system and the throttle valve so that, while the starter is operating, the throttle will be closed and, as soon as the engine starts to run under its own power and the starter ceases to operate, the throttle valve 45 will resume whatever position is forced on it by the auxiliary fuel feeding system.

As shown in Fig. 1, this connection is of an 45 electrical nature and comprises an arm 73 rigid with the throttle shaft 21 and connected by means of a link 74 to a bar 76 running through the 50 previously referred to solenoid 17. Thus, whenever the switch 16 is closed, the solenoid will be energized to pull the arm 73 until the 55 throttle valve is substantially closed so that a minimum of air will be drawn into the intake manifold 11 and so that the mixture may be at its very richest.

The effect of the solenoid 17 in rotating the 60 throttle shaft into throttle closed position is designed to overcome the force of the spring 72 so that the yieldable choke regulated throttle operating connection through the pin 69 is rendered inoperative but, as soon as the switch 16 is opened, the solenoid is de-energized and the 65 spring 72 forces the throttle open again. The de-energizing of the solenoid 17 occurs when the 70 starter switch 16 is opened, which in turn usually happens as soon as the engine starts to run, particularly if the starting motor circuit is automatically controlled as in the manner illustrated in my copending application Serial No. 582,806, filed December 23, 1931.

Under these conditions, the control of the 75 throttle may be left to the automatic functioning of the mechanism which I have described and

this is particularly advantageous under certain conditions where the vehicle operator is not entirely familiar with the proper degree of throttle opening necessitated by cold weather starting conditions.

Fig. 5 shows a modification of the connection between the starter and the throttle which is mechanical in nature. I have shown a pedal 77 which may be the starting pedal, for regulating the starting motor switch 16 in the desired manner. Thus, as the pedal is depressed, a shoulder 78 thereon engages a bell-crank 79 pivoted as at 80 and connected to a link 74 and the arm 73, as previously described. Thus, as soon as the 85 starting switch is closed, the throttle is also closed and, as soon as the starting switch 16 is opened under the influence of a suitable spring such as the one shown at 81, the spring 72 again becomes effective as it did with the electrical 90 connection between the starting system and the 95 throttle.

With the electrical connection, functioning of the 100 throttle 19 through the conventional throttle operating mechanism 82, is not interfered with because the rod 76 is free to slide in the solenoid 17 and, with the mechanical connection shown in Fig. 5, the same condition occurs because the shoulder 78 on the pedal 77 is, when the 105 starter is not operating, above the range of movement of the bell-crank 79.

It will thus be seen that I have provided means 110 operative during operation of the starting system to enrich the mixture and means operative after the starting system has ceased to function, to decrease the richness of the mixture.

Although the invention has been described in 115 connection with a specific embodiment, the principles involved are susceptible of numerous other applications which will readily occur to persons skilled in the art. The invention is therefore to 120 be limited only as indicated by the scope of the appended claims.

What I claim is:

1. In a fuel feeding system for engines, the 125 combination with a throttle valve, of priming means operatively connected with said valve to urge the latter into open position during the priming of said engine, and engine starter mechanism connected to substantially close said throttle valve when effective.

2. In a fuel feeding system for engines, the 130 combination of throttle valve means, priming means acting when effective to urge said valve means into open position, starter mechanism for said engine, and a connection actuated by said 135 starter mechanism when effective to close said throttle valve.

3. In a fuel feeding system for engines, the 140 combination of throttle valve means, priming means connected with the system beyond the 145 throttle valve means, a connection between the priming means and the valve means tending to urge the valve means into open position when said priming means is rendered operative, engine starter mechanism, and a connection actuated by the engine starter mechanism when effective for closing said valve means.

4. In a fuel feeding system for engines, the 150 combination of a means for feeding metered air and fuel, a throttle valve regulating the volume 155 of metered air and fuel moving through the system, an auxiliary fuel induction system beyond the throttle valve, means for substantially closing said valve during engine starting, and means 160 coacting with said auxiliary induction system to 165

open said throttle valve a limited extent when said closing means is released.

5. In a fuel feeding system for engines, the combination with means controlling the quantity 5 of combustible mixture supplied to said engine, of priming means for said engine, an operative connection between said control means and said priming means for increasing the quantity of mixture supplied to said engine during priming thereof, and engine starter mechanism operatively associated with said control means for decreasing the quantity of mixture supplied to said engine when the latter is started.

6. In a fuel feeding system for vaporized charge engines, the combination with means controlling the quantity of combustible mixture of air and liquid fuel supplied to said engine, of priming means operable to supply said engine with an excess of liquid fuel to facilitate starting, a connection 10 between said priming means and said control means tending to reduce the quantity of mixture supplied to said engine during priming thereof, mechanism for starting said engine, and a connection between said starting mechanism 15 and said control means tending to reduce the quantity of mixture supplied to said engine during operation of said starting mechanism.

7. In a fuel feeding system for vaporized charge engines, the combination with means controlling 30 the quantity of combustible mixture of air and liquid fuel supplied to said engine, of priming means operable to supply said engine with an excess of liquid fuel to facilitate starting, a connection between said priming means and said control means tending to reduce the quantity of mixture supplied to said engine during priming thereof, mechanism for starting said engine, and

a connection between said starting mechanism and said control means tending to reduce the quantity of mixture supplied to said engine during operation of said starting mechanism, said last named connection opposing and overcoming 5 the action of said first named connection.

8. In a fuel feeding system for vaporized charge engines, the combination with means controlling the quantity of combustible mixture of air and liquid fuel supplied to said engine, of priming 10 means operable to supply said engine with an excess of liquid fuel to facilitate starting, a yielding connection between said priming means and said control means urging the latter to a position corresponding to increased mixture supply to said 15 engine, mechanism for applying torque to said engine to start the same, and means associated with said mechanism opposing the action of said yielding connection when torque is applied to said engine.

9. In a fuel feeding system for vaporized charge engines, the combination with means controlling the quantity of combustible mixture of air and liquid fuel supplied to said engine, of priming means operable to supply said engine with an 25 excess of liquid fuel to facilitate starting, a yielding connection between said priming means and said control means urging the latter to a position corresponding to increased mixture supply to said 30 engine, mechanism for applying torque to said engine to start the same, and an operative connection between said mechanism and said control means effective to reduce the quantity of mixture supplied to said engine to a minimum during application of starting torque to said engine. 35

CLYDE R. PATON.
